UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 13,848, dated April 10, 1883.

Application filed March 8, 1883. Term of patent 14 years.

To all whom it may concern:

Be it known that I, HERMAN IHLENBURG, (assignor to MACKELLAR, SMITHS & JORDAN,) of the city and county of Philadelphia, Penn-

sylvania, have invented and produced a new and original Design for a Font of Printing-Type, of which the following is a specification.

The nature of my design is clearly shown in the accompanying typographic impression, to which reference is made; and it consists of a letter of the class known as "text," provided with the curved line terminating in a dot, as shown in the A, B, F, I, J, L, M, N, P, R, S, T, U, W, Y, and 2. The A is also ornamented upon the left by the flourish. The B, C, D, E, G, H, K, O, Q, T, U, and V are ornamented by a light vertical line extending from the top to the bottom of the letter, while the F, I, J, L, M, N, P, R, W, and Y have the heavy up-and-down lines shaded by a lighter line. The D, E, G, M, N, P, T, U, V, and W are orna-

mented within the face by the waving-like figure placed about centrally, and the F, I, J, M, X, and 2 by the short horizontal lines placed about centrally.

In the lower-case the character of the design is preserved notably in the c, e, f, h, j, m, n, r, v, x, y, and z, and also in the numerals, more particularly in the 1, 2, 3, 4, and 5. Two affixes to be used in connection with the font are shown upon the right of the lower-case, the one consists of four small heavy dots placed transversely, the other simply of a small heavy dot.

Having now described my invention, I claim as new—

The design for a font of printing-type, as shown and described.

HERMAN IHLENBURG.

In presence of—

C. F. HUCH,

HERMAN METIUS.
